UNITED STATES PATENT OFFICE.

CHARLES J. AHRENFELDT, OF NEW YORK, N. Y.

DESIGN FOR A PLATE.

SPECIFICATION forming part of Design No. 30,522, dated April 11, 1899.

Application filed January 11, 1899. Serial No. 701,889. Term of patent 3½ years.

To all whom it may concern:

Be it known that I, CHARLES J. AHRENFELDT, a citizen of the United States, residing in the city of New York, county of New York, 5 and State of New York, have invented and produced a new and original Design for a Plate, of which the following is a specification, reference being had to the accompanying drawings, forming a part hereof, like letters referring to like parts in each figure of the same.

In the said drawings, Figure 1 is a plan view of a plate embodying my design. Fig. 2 is a cross-section of the same on the line 2-2 of 15 Fig. 1.

The brim of the plate A is provided with four sets of indentations B in its periphery—four in each set—giving it a wave-like contour, with three small waves and one large 20 wave alternated. A radial depression G extends from the crest of each of the small waves a short distance toward the center and is merged in the surface of the plate near the annular step C. Bordering the step C upon 25 the outside is a series of ornamentals consisting of the ornaments D, E, and F, the ornaments D being two in number and diametrically opposite each other and at right angles to the ornaments E, which are also two

in number, while the ornaments F are four 30 in number, being alternated with D and E around the brim.

D consists of a central panel D', of three vertical divisions d, bordered on either side by a horizontally-disposed scroll D², having 35 its ends turned upwardly and terminating in involutes, said scrolls being supplemented at their outer ends by a stem D³, provided with leafed and floral ornamentations.

E consists of a scallop-like centerpiece E', 40 with ornaments at either side similar to those of D.

F consists of three parts, F' resembling an inverted C, with small projections on the inner side disposed above the others, F² and F³, 45 which are tendril-like in form.

The part of the plate within the step C presents an undecorated plain surface.

What I claim is—

The design for a plate herein shown and 50 described.

Signed at the city of New York this 4th day of January, 1899.

CHARLES J. AHRENFELDT.
